17 Claims. (Cl. 260—679)

This application is a continuation-in-part of application Serial No. 757,740, filed August 28, 1958, now abandoned, and Serial No. 860,794, filed December 21, 1959, now abandoned and combines both of said applications into a single application.

This invention relates to an improved process for making acetylene and olefins by partial combustion of hydrocarbons with oxygen-containing gas.

In the drawings, the figure relates to the apparatus of application Serial No. 757,740.

The techniques employed hitherto comprise mixing the hydrocarbon with oxygen, each being separately preheated, and introducing the mixture into a furnace in which the flame is extinguished by means of a water jet after a few hundredths of a second. This has been practiced on a commercial scale at a pressure very near atmospheric. Since the proportion of acetylene in the gases thus obtained does not in practice exceed 9%, the gases are then compressed to facilitate separation of acetylene by absorption in selective solvents. However, the compression of the gas requires a marked consumption of energy. It also involves technical difficulties caused by the presence of carbon black and tars, which hinder the regular operation of the apparatus.

A principal object of the present invention is to obviate these difficulties by carrying out the partial combustion of hydrocarbons with oxygen under a pressure which is sufficient for the successful subsequent separation of acetylene from the gases. This technique is contrary to the prior belief that the chemical equilibrium of the reaction resulting in acetylene would be hindered by an increase in pressure. In fact, some prior processes are carried out under vacuum. Contrary to this commonly held view I have found that a superatmospheric pressure of at least two atmospheres, and especially in the range of two to six atmospheres, has very significant advantages. When the partial combustion of hydrocarbon (e.g.) methane with oxygen is carried out under a pressure of 3 to 4 atm., the yield of acetylene is practically the same as that obtained under atmospheric pressure at a given flow-rate of the two gases.

Since the natural gas is generally available under a high pressure, its expansion down to from 3 to 4 atm. in an ejector can be used in order to compress oxygen to the same pressure. In the drawings the ejector is shown at 6. The compression of oxygen by means of such a device also makes it possible to obtain intimate mixing of the two gases in safest possible way, since, if the methane flow fails, the oxygen flow would be stopped automatically.

The gaseous mixture is introduced into the combustion chamber through a distributor 7 at a rate higher than the propagation rate of the flame. The upper part of the distributor 7 consists of a metallic plate 70 to which a number of parallel pipes 71 made of a special steel resistant to high temperatures are fixed. The space between the pipes is filled with a refractory material 72. A stable flame is obtained which adheres to the lower refractory wall 73 of the distributor, which is heated to a temperature of 1400° C. This provides regular and safe operation.

The flame is extinguished by water spouts 9, at a tem-

2

perature of 120–130° C., since it has been found that the carbon black contained in the gas is wetted only by water at a temperature higher than 100° C. By adopting this precaution carbon black can be easily separated from the gas by washing with water without filtering.

Another advantageous feature of the process is that the heat removed upon cooling the gases coming from the partial combustion of the hydrocarbons under a pressure of 6 atm. is used to heat a considerable amount of water to a temperature of 120° C. This water can be advantageously employed to regenerate the selective solvents used to remove acetylene from the residual gases. A considerable saving in steam is thus obtained, in comparison with processes in which the partial combustion is carried out under atmospheric pressure.

After the removal of carbon black, the gas is cooled with water, but it still contains aromatic hydrocarbons and tars which would be absorbed in the selective solvents used for absorbing acetylene, thereby altering their physico-chemical properties after a brief time.

When operating under atmospheric pressure according to prior processes, the gases must be cooled to from –20° to –30° C. to eliminate such hydrocarbons. In contrast, when the gases are available under a pressure of from 3 to 4 atm. a satisfactory purification is obtained by cooling to a temperature of 0° C., thus realizing a considerable saving in power consumption in the cooling plant.

A preferred embodiment of this aspect of the invention is more specifically described as follows:

30 Methane available under high pressure is decompressed to 16 atm. in the pressure reducing valve 1 and, after pre-heating to about 500° C. in the heat exchanger 4, is introduced into the ejector 6.

Oxygen available under a pressure of 1 atm., after pre-heating to 500° C. in the heat exchanger 5, is sucked into the furnace 60 by ejector 6. By suitably regulating the valves 2 and 3, a mixture consisting of 62% methane and 38% oxygen under a pressure of 6 atm. is thus obtained. The gaseous mixture passes through the pipes 71 of distributor 7, whose lower part consists of a refractory material 72–73, and is introduced into the combustion chamber 8 where the temperature is brought to 1400° C. The flame is extinguished with water sprayed through the nozzles 9 by the pump 10.

45 The temperature of the circulating water is kept at 120° C. and the separated carbon black is discharged through valve 11.

The gas produced by partial combustion of methane and containing from 8.5 to 9% acetylene is cooled in the scrubber 13. The water collected on the bottom, at a temperature of 120° C., is passed upwardly by a pump 101 to release its heat in the heat exchanger 12 where the selective solvent used for the absorption of acetylene is heated.

55 The gas leaving the tower 13 is further cooled with water in the tower 15 and then, with cooling mixtures, in the tower 16 to 0° C. to remove aromatics and tars. The gas purified from carbon black and aromatics and tars is finally subjected to a washing with selective solvents in order to separate acetylene. Heat exchangers 14 and 17 are employed to preheat the replenishing water introduced into towers 13 and 15.

60 The extraction of acetylene with selective solvents can be carried out in a conventional gas scrubbing tower 18 similar to towers 13 to 16. The solvent is withdrawn at 180 and passed through heat exchanger 12 and acetylene stripper 19, from which pump 181 returns it to tower 18 through cooler 20. Note Fauser Patent 2,834,431. The selective solvents used are the conventional ones described in the prior art.

70 Pumps 101, 102, 103 recirculate the scrubbing media to

the tops of the towers 13, 14, 15. Valves 111, 211, 311 remove separated carbon black or aromatics.

This aspect of the invention is in the same general field as U.S. Patent 2,894,602 of July 14, 1959, which describes acetylene, ethylene, and CO_2 separation and recovery system utilized here.

The procedure usually employed in the manufacture of acetylene and olefines from liquid or gaseous hydrocarbons comprises carrying out a partial combustion with oxygen at a temperature higher than 1500°C ., and then cooling the combustion products as quickly as possible, in order to prevent dissociation of the acetylene.

Such process has hitherto been operated at a pressure quite close to atmospheric, since it was thought that the equilibrium of the reaction giving rise to formation of acetylene would be hindered by pressure increase. And further, the rapid quenching was performed by extinguishing the flame by injecting water into the furnace. The entire heat of the combustion products was effectively lost, in its removal by the cooling water.

This aspect of my invention relates to a process providing a rational utilization of the heat available in the products of partial combustion. The process entails two main features: the first consists in carrying out the incomplete combustion under an absolute pressure of from 2 to 6 atmospheres; the second consists in quenching the partial combustion products in a two stage operation: the first stage being with the aid of a hydrocarbon containing 2 or more carbon atoms, and then with water.

I have found that when incomplete combustion of either gaseous or liquid hydrocarbons with oxygen is carried out under pressure of from 2 to 6 or preferably from 3 to 4 atmospheres, the acetylene and ethylene yields are practically as high as the yields obtained at atmospheric pressure. For example, when partial combustion is operated under a pressure of 4 atmospheres, the gas quenching permits high heat recovery in the form of hot water at a temperature as high as 130°C ., which can be conveniently utilized to regenerate solvents employed in the acetylene separation from residual gases.

In addition, carrying out the partial combustion under pressure results in considerable saving of power. Ordinarily, the gases leaving the furnace must be compressed, to facilitate separation of acetylene, by the conventional absorption in a solvent at a low temperature. Such compression is no longer necessary if as with the instant process the gases leave the furnace already under pressure.

The said two-stage quenching of the partial combustion products, carried out first with a hydrocarbon and then with water, can be employed in conjunction with any type of furnace used for producing acetylene and ethylene.

As is known, ethylene is formed at a lower thermal level than acetylene. Therefore, when, in said first stage quenching step, finely atomized liquid fuel is sprayed into the furnace through a series of holes uniformly arranged upon one or more planes normal to the furnace axis, before said water is injected, the yield of acetylene, olefines and synthesis gas is successfully increased, and to an extent substantially effecting the economic performance of the process. By this means, the output of acetylene and olefines obtained by pyrolysis, i.e. cracking, at a temperature of 1500°C . will be augmented by a further yield, obtained by taking advantage of the heat removed from the combustion products, in cooling from 1500° to 800° – 700°C .

In order to prevent acetylene decomposition, as soon as pyrolysis is finished the gases should be quickly quenched down to a temperature of 150 – 140°C ., with the aid of said water injection.

The optimum increase in production of acetylene, olefines and synthesis gas obtained by this procedure depends upon a number of factors. For instance, it is dependent upon the properties of the hydrocarbons employed in the primary and secondary pyrolysis, on the preheating temperature, and its range. Under optimum conditions the

yields of acetylene and ethylene can exceed by 50% the yields obtained by the conventional procedure, in which only water cooling is employed. This yield increase represents a real saving, since it is obtained with no further consumption of oxygen and heating fuel.

Moreover, this procedure permits variation, to a substantial extent, of the acetylene to ethylene ratio by a suitable adjustment of the hydrocarbon feed in the primary and secondary pyrolysis.

Working example

The high-temperature gas obtained in a process producing acetylene by partial oxidation of methane with oxygen, was rapidly cooled down to about 750°C . by injection of gasoline (petrol) in the proportion of 130 kg. of gasoline for 1000 Nm^3 of methane. The gas mixture, constituted by the gas obtained from the thermal decomposition of the gasoline and the gas formed in the partial oxidation of methane, was rapidly cooled down to about 150°C . by means of water. The volume of gas produced from the methane increased by about 140 Nm^3 for every 100 kg. of gasoline introduced. The composition of the gas obtained from the thermal decomposition of the gasoline is as follows:

	Nm. ³ /100 kg. petrol (gasoline)
C_2H_2	19.23
C_2H_4	30.00
CO_2	2.60
CO	9.80
30 H_2	57.83
CH_4	19.67
C_3H_6	1.20
	140.33

Hence the following yields resulted:

C_2H_2	22.32 kg./100 kg. petrol (gasoline).
C_2H_4	37.50 kg./100 kg. petrol (gasoline).
Other gases	$367 \times 10^3 \text{ Kcal.}/100 \text{ kg. petrol.}$

The following computation evidences the advantage of the process. Suppose the following prices:

Gasoline (petrol)	20 lire/kg.
Acetylene	80 lire/kg.
Ethylene	60 lire/kg.
Calories in the combustible gas	2 lire/1000 Kcal.

Consider a plant having a potentiality of $100,000 \text{ Nm}^3/\text{day}$ of CH_4 ; when using the instant process, the lire consumption for quenching is:

50 $13,000 \text{ kg. of gasoline (petrol)} = 260,000 \text{ lire/day}$ while one obtains—

	Lire
2,900 kg. of C_2H_2	232,000
4,875 kg. of C_2H_4	292,500
55 $11,800 \text{ Nm}^3$ of gases	95,000
	619,500

Hence a net profit of $360,000$ lire/day is obtained, that is to say, $120,000,000$ lire a year.

60 The gases subjected to quenching are at the pressure obtaining in the reaction zone, except for any normally small pressure losses in passing from the reaction zone to the quenching zone. The preferred quenching temperature range is about 130° – 200°C .

65 Application Serial No. 814,146 which was copending with the parent applications hereof is now Patent No. 3,140,323 of July 7, 1964, and describes a companion process in which the combustion gases are quenched, in one or two steps, by introducing atomized mineral oil, preferably having a boiling point above 250°C . The quenching is preferably under conditions favoring cracking, to increase the yields of acetylene and ethylene. The oil used in the first stage of the quenching lowers the temperature of the combustion gases to about 700° – 800°C .

70 75 The oil employed in the second stage of the quenching

lowers the temperature of the combustion gases to below 200° C.

I claim:

1. In a process for producing acetylene by partial combustion of methane with oxygen in a combustion zone, at a temperature and reaction duration producing acetylene, the improvement comprising separately preheating the methane and oxygen, passing the preheated methane, which is under pressure, through a restricted passage, the preheated oxygen being fed to said passage at substantially atmospheric pressure, the methane and oxygen being mixed thereby, the flow of oxygen through said passage automatically ceasing when the flow of methane fails, passing the gas mixture through a plurality of passages, in parallel arrangement, into a combustion zone, the velocity of the gas mixture in said passages being greater than the propagation rate of the flame in the combustion zone, the combustion zone being adjacent the exit of the gas mixture from said plurality of passages, extinguishing said flame by means of a liquid water jet the temperature of which is above 100° C., and passing the combustion gases through a cooling and water scrubbing zone, and subsequently washing the gas with a solvent for the acetylene to separate the acetylene, said partial combustion being carried out at a pressure maintained at 3 to 4 atmospheres pressure, the pressure in the flame extinguishing zone, the water scrubbing zone, and in the zone of solvent extraction of the acetylene being at a pressure greater than atmospheric, being substantially the pressure of delivery from the preceding steps of the process.

2. The process of claim 1, including passing the scrubbing water heated in the cooling and scrubbing zone in indirect heat exchange with the solvent passed from the acetylene extraction step to a solvent regeneration step in which the acetylene is stripped from the solvent.

3. In a process for producing acetylene by partial combustion of a hydrocarbon gas with oxygen, at a temperature and reaction duration producing acetylene, the improvement comprising separately preheating the oxygen and the hydrocarbon gas, the hydrocarbon gas being at a higher pressure than the oxygen, compressing the oxygen by mixing with expanding hydrocarbon gas, the partial combustion being carried out at a pressure of at least two atmospheres and at about 1400° C., the mixture of oxygen and hydrocarbon gas being fed at a velocity higher than the propagation rate of the combustion flame, extinguishing the combustion flame and separating carbon black by introducing jets of liquid water, the water being at a temperature above 100° C., the pressure in the flame extinguishing step being at about two to six atmospheres, scrubbing the gases which have been freed of carbon black with a selective solvent to remove acetylene, said scrubbing being carried out at superatmospheric pressure below that at which the partial combustion is carried out.

4. In a process for producing acetylene by partial combustion of a hydrocarbon gas with oxygen, at a temperature and reaction duration producing acetylene, the improvement comprising separately preheating the oxygen and the hydrocarbon gas, the hydrocarbon gas being at a higher pressure than the oxygen, compressing the oxygen by mixing with expanding hydrocarbon gas, the partial combustion being carried out at a pressure of about 3 to 4 atmospheres, and at about 1400° C., the mixture of oxygen and hydrocarbon gas being fed through a passage at a velocity higher than the propagation rate of the combustion flame, extinguishing the combustion flame and separating carbon black by introducing jets of liquid water adjacent the exit of the passage, the water being at a temperature above 100° C., the pressure in the flame extinguishing step being about 3 to 4 atmospheres, scrubbing the gases which have been freed of carbon black with a selective solvent to remove acetylene, said scrubbing being carried out at superatmospheric pressure below that at which the partial combustion is carried out.

5. In a process for producing acetylene by partial combustion of hydrocarbons with oxygen, the improvement comprising carrying out the combustion at a pressure of two to six atmospheres and extinguishing the flame under said pressure by means of liquid water at a temperature above 100° C., and thereafter scrubbing and cooling the gases with water while still at superatmospheric pressure, the cooling being at least sufficiently low to condense the steam in the quenched gases, and subsequently removing the acetylene from the gases by a solvent for the acetylene, the heat recovered by the scrubbing and cooling step being utilized to heat the solvent to assist in removal of acetylene from it.

6. In a process for producing acetylene by partial combustion of methane with oxygen in a combustion zone, at a temperature and reaction duration producing acetylene, the improvement comprising separately preheating the methane and oxygen, passing the preheated methane, which is under pressure, through a restricted passage, the preheated oxygen being fed to said passage at substantially atmospheric pressure, the methane and oxygen being mixed thereby, the flow of oxygen through said passage automatically ceasing when the flow of methane fails, passing the gas mixture through a plurality of passages, in parallel arrangement, into a combustion zone, the velocity of the gas mixture in said passages being greater than the propagation rate of the flame in the combustion zone, the combustion zone being adjacent the exit of the gas mixture from said plurality of passages, extinguishing said flame and removing carbon black by means of a liquid water jet the temperature of which is above 100° C., and passing the combustion gases through a cooling and scrubbing zone in which the water is heated to a temperature above 100° C., removing aromatic hydrocarbons by cooling to about 0° C., and subsequently washing the gas with solvents for the acetylene to separate the acetylene, said partial combustion being carried out at 3 to 4 atmospheres pressure, the pressure in the carbon black removal and the water scrubbing zone, in the aromatic hydrocarbon removal and in the zone of solvent extraction of the acetylene being at a pressure greater than atmospheric, being substantially the pressure of delivery from the preceding steps of the process.

7. In a process for producing acetylene by partial combustion of hydrocarbons with oxygen, the improvement comprising carrying out the combustion at a pressure of from about two to six atmospheres and extinguishing the flame under pressure by means of liquid water which is at a temperature above 100° C., whereby the sensible heat of the water is made available for recovery.

8. In a process for producing acetylene by partial combustion of a hydrocarbon with oxygen in a combustion zone, at a temperature and reaction duration producing acetylene, the improvement comprising separately preheating the hydrocarbon and oxygen, passing the preheated gaseous hydrocarbon, which is under pressure, through a restricted passage, the preheated oxygen being fed to said passage at a pressure of about 1 atm., the hydrocarbon and oxygen mixing in said passage, the flow of oxygen through said passage automatically ceasing when the flow of hydrocarbon fails, passing the gas mixture through a plurality of passages, in parallel arrangement, into a combustion zone, the velocity of the gas mixture in said passages being greater than the propagation rate of the flame in the combustion zone, the combustion zone being adjacent the exit of the gas mixture from said plurality of passages, extinguishing said flame and removing carbon black by means of a liquid water jet the temperature of which is above 100° C., and passing the combustion gases through a cooling and water scrubbing zone, and thereafter washing the gas with a solvent for the acetylene to separate the acetylene, said partial combustion and flame extinction being carried out at a pressure maintained at 3 to 4 atmospheres pressure, the pressure in the water scrubbing zone and in the zone of solvent extraction of the

acetylene being at a pressure greater than atmospheric, being substantially the pressure of delivery from the preceding steps of the process.

9. In a process for producing acetylene by partial combustion of methane with oxygen in a combustion zone, at a temperature and reaction duration producing acetylene, the improvement comprising separately preheating the methane and oxygen, mixing the methane and oxygen, passing the gas mixture through a passage into a combustion zone, the velocity of the gas mixture in said passage being greater than the propagation rate of the flame in the combustion zone, the combustion zone being adjacent the exit of the gas mixture from said passage, extinguishing said flame and removing carbon black by means of a liquid water jet the temperature of which is above 100° C., passing the combustion gases through a cooling and scrubbing zone, and subsequently washing the gas with a solvent for the acetylene to separate the acetylene, said partial combustion and said flame extinguishing being carried out at a pressure greater than two atmospheres and not more than six atmospheres, the pressure in the zone of solvent extraction of the acetylene being at a pressure greater than two atmospheres.

10. A method of making acetylene and ethylene, comprising subjecting a hydrocarbon to cracking by partial combustion in a reaction zone with a free-oxygen containing gas, at a temperature of at least 1500° C., at a pressure of two to six atmospheres, to produce acetylene, in a second zone immediately quenching the acetylene containing gases as they leave said reaction zone at a temperature of at least 1500° C., by spraying said gases with a liquid hydrocarbon in the form of droplets, with resultant production of ethylene and further production of acetylene by the cracking of said liquid hydrocarbon, the temperature being thereby decreased to 700-800° C., and then immediately quenching the reaction gases as they leave the second zone with a spray of water to 130-200° C., to prevent acetylene decomposition, the quenching steps also being carried out at two to six atmospheres.

11. The process of claim 10, the first hydrocarbon being natural gas, the second being gasoline.

12. A method of making acetylene and ethylene, comprising subjecting a hydrocarbon to cracking by partial combustion in a reaction zone with a free-oxygen containing gas, at a pressure of two to six atmospheres, to produce acetylene, in a second zone immediately quenching the acetylene containing gases as they leave said reaction zone by spraying said gases with a liquid hydrocarbon in the form of droplets, with resultant production of ethylene and further production of acetylene by the cracking of said liquid hydrocarbon, and then immediately quenching the reaction gases as they leave the second zone with a spray of water to prevent acetylene de-

composition, the quenching steps also being carried out at two to six atmospheres.

13. The process of claim 12, the quenching being carried out at a pressure of about 3 to 4 atmospheres.

14. The process of claim 12, the quenching being carried out at a pressure of about 3 atmospheres.

15. A method of making acetylene and ethylene, comprising subjecting a hydrocarbon to cracking by partial combustion in a reaction zone with a free-oxygen containing gas, at a temperature of at least 1500° C., at a pressure of two to six atmospheres, to produce acetylene, in a second zone immediately quenching the acetylene containing gases as they leave said reaction zone at a temperature of at least 1500° C., by reacting said gases with a hydrocarbon having more than two carbon atoms, with resultant production of ethylene and further production of acetylene by the cracking of the latter hydrocarbon, the temperature being thereby decreased to 700-800° C., and then immediately quenching the reaction gases as they leave the second zone with a spray of water to 130-200° C., to prevent acetylene decomposition, the quenching steps being carried out at above one atmosphere, being at a pressure obtaining in the said reaction zone less any pressure loss in passing from said reaction zone to the quenching.

16. A method of making acetylene and ethylene, comprising subjecting a hydrocarbon to cracking by partial combustion in a reaction zone with a free-oxygen containing gas, at a temperature of at least 1500° C., at a pressure of two to six atmospheres, to produce acetylene, in a second zone immediately quenching the acetylene containing gases as they leave said reaction zone at a temperature of at least 1500° C., by spraying said gases with a liquid hydrocarbon in the form of droplets, with resultant production of ethylene and further production of acetylene by the cracking of said liquid hydrocarbon, the temperature being thereby decreased to 700-800° C., and then immediately quenching the reaction gases as they leave the second zone with a spray of water to 130-200° C., to prevent acetylene decomposition, the quenching steps being carried out at above one atmosphere, being at a pressure obtaining in the said reaction zone less any pressure loss in passing from said reaction zone to the quenching, and passing the quenched reaction gases without release of pressure to recovery process in which acetylene and olefines are separated by extraction with solvents.

17. The process of claim 16, the first hydrocarbon being natural gas, the second being gasoline.
